WITNESS:

J. J. L. Wright

UNITED STATES PATENT OFFICE.

WILLIAM JOHN HANEY, OF NORTH VERNON, INDIANA.

CLACKING INSERT FOR SHOES.

Application filed May 26, 1926. Serial No. 111,840.

This invention relates to a clacking device for a shoe, the general object of the invention being to provide means for making a noise as the wearer of the shoe dances.

5 Another object of the invention is to provide means whereby the noise produced by the device can be regulated by inserting one or more loose members in the device before the same is inserted into the heel of the shoe.

10 This invention also consists in certain other features of construction and in the combination and arrangement of the several parts, to be hereinafter fully described, illustrated in the accompanying drawings and 15 specifically pointed out in the appended claims.

In describing my invention in detail, reference will be had to the accompanying drawings wherein like characters denote 20 like or corresponding parts throughout the several views, and in which:—

Figure 1 is a view of a shoe with its heel broken away to show the device in use.

Figure 2 is a section on line 2—2 of Figure 1.

25 Figure 3 is a plan view.

Figure 4 is a perspective view of the casing with two of the movable members outside of the same.

30 Figure 5 is a view of the casing turned over.

In these views, 1 indicates a casing, the under part 2 of which is made in the shape of a heel with its sides extended to form the 35 flanges 3. The casing is formed with one end open and this end is curved to conform to the curved end of the under part. A large central opening 4, with beveled edges, is formed in the bottom of the casing and 40 smaller openings 5 are made in the under part around the edges thereof to receive nails for fastening the device in a hole in the heel. The top of the casing is also provided

with a hole 6 adjacent its open end which registers with one of the holes 5 so that a 45 nail 7 can be passed through the two holes to hold one or more plates 8 in the casing. Figures 1 and 2 show a single plate in the casing, while Figure 4 shows two plates ready to be placed in the casing. After the 50 plate or plates, is put in place, the nail is passed through the two holes and bent over, as shown in Figure 1. This will hold the plates in position. A hole is then cut in the heel, with a countersunk portion for the 55 flanges 3 and the device placed therein, with its lower face flush with the surface of the heel. The device is fastened in the hole by nails 9 or the like and it will be seen that when the wearer of the shoes provided with 60 the invention dances, the movement of the plate 8 in the casing will make a clacking sound.

It is thought from the foregoing description that the advantages and novel features 65 of my invention will be readily apparent.

I desire it to be understood that I may make changes in the construction and in the combination and arrangement of the several parts, provided that such changes fall within 70 the scope of the appended claims.

What I claim is:—

1. An attachment for a dancing shoe comprising a hollow casing secured in the heel flush with its base, and provided with 75 an opening at the base, and a freely movable resonant plate nesting over the opening.

2. In a dancing shoe, a hollow casing buried flush in the heel, and opening in the base of the hollow casing of less area than 80 the casing bottom, a movable plate resting on the edges of said opening and an auxiliary opening at the rear of the casing.

In testimony whereof I affix my signature.

WILLIAM JOHN HANEY.
